UNITED STATES PATENT OFFICE.

JOSEPH F. SCHIMEK, OF WORCESTER, MASSACHUSETTS, ASSIGNOR TO CASHIKO MACHINE COMPANY, OF WORCESTER, MASSACHUSETTS, A CORPORATION OF MASSACHUSETTS.

DRIVE MECHANISM FOR WINDING MACHINES.

Application filed September 30, 1925. Serial No. 59,734.

To all whom it may concern:

Be it known that I, JOSEPH F. SCHIMEK, a citizen of the United States, residing at Worcester, in the county of Worcester and 5 Commonwealth of Massachusetts, have invented a new and useful Improvement in a Drive Mechanism for Winding Machines, of which the following, together with the accompanying drawings, is a specification.

10 My invention relates to an improved drive mechanism for winding machines and is particularly adapted for use in connection with machines, such as tape condensers and apron condensers, which deliver roving, or 15 yarn, to be wound on suitable spools at the delivery end of the machine.

The object of my invention is to provide an improved driving mechanism whereby the winding spools may be rotatably driven by 20 means of drums in peripheral engagement with the material being wound on the spools. Specifically, my invention provides an arrangement whereby spools provided with heads of relatively large diameter may be 25 driven by drums of a reduced diameter which is approximately half that of the spools, thus making it possible to mount the driving drums between the condenser frames with sufficient spacing therebetween to 30 permit the operator to reach between the drums to care for the machine. The above and other advantageous features of my invention will hereinafter more fully appear, reference being had to the accompanying 35 drawings in which—

Fig. 1 is a view in rear elevation of a portion of a condenser provided with drums and spools driven in accordance with my invention.

40 Fig. 2 is a view in end elevation of the parts shown in Fig. 1.

Fig. 3 is a vertical sectional view on the line 3—3 of Fig. 1, looking in the direction of the arrows.

45 Fig. 4 is a fragmentary view, on an enlarged scale, showing the details of the mounting of one of the driving drums shown in Fig. 1.

50 Fig. 5 is a horizontal sectional view along the line 5—5 of Fig. 4, looking in the direction of the arrows.

Fig. 6 is a vertical sectional view along the line 6—6 of Fig. 5, looking in the direction of the arrows.

Like reference characters refer to like parts in the various figures.

Referring first to Figs. 1, 2 and 3, a portion of a tape condenser is shown as comprising spaced end frames 1, 1, between which are supported a number of pairs of 60 cooperating winding spools 2 and driving drums 3, the spools 2 being so supported as to receive the rovings, or yarn, from the different sets of aprons of the machine as indicated in dotted lines in Fig. 2. Each 65 winding spool 2 is provided with enlarged heads 4 which are spaced apart for a distance greater than the length of the corresponding drum 3, so that a drum 3 may be received between the heads 4 of the spool 70 2 to frictionally engage a central barrel 5 of the spool, or the material being wound thereon.

The above described general arrangement of parts is usual in machines of the tape 75 condenser type and is shown to illustrate my invention which, of course, may be used with other types of machines employing winding spools. In machines of this type, it has been heretofore customary to drive 80 the drums 3 directly by means of pulleys mounted on the shafts of the drums, but with this arrangement, it has been found necessary to make the drums of substantially the same diameter as the spool heads in 85 order that the periphery of each drum may engage the periphery of the barrel of any empty spool. The object of the present invention is to provide an improved mechanism for driving the drums 3 in such a manner that the diameter of the drums may be reduced to substantially one-half the diameter of the spool heads 4, thereby permitting 90 such a spacing of the driving drums as to give ready access to the operating parts of 95 the machine.

With my improved drive mechanism, each drum 3 is rotatably supported at its ends by means of brackets 6 mounted on a rod 7 extending across the machine between the frame members 1, and as each bracket 6 is constructed in exactly the same manner, only one bracket will be described in detail, with reference to Figs. 4, 5 and 6, which show only a portion of a drum 3 and its associated parts, on an enlarged scale.

As best shown in Figs. 5 and 6, each bracket 6 provides an upwardly extending

portion 8 which is bent laterally at 9 to permit the reception of a cylindrical bearing 10 within the open end of the drum 3, it being evident from Fig. 1, that each pair 5 of brackets 6 provides oppositely facing bearings 10. In order to receive support from the bearings 10, the drum is closed at each end by a head 11 which provides a central hub portion 12 carrying a pivot stud 10 13, an enlarged portion 14 of which is received in a bearing 10. The stud 13 is secured to the hub 12 by means of a nut 15 coacting with a collar 16. The head 11 also provides an annular flange 17 surrounding 15 the bearing 10, which flange 17 is provided with a plurality of spaced peripheral openings 18, whereby a driving force may be applied to the periphery of the drum 3 by mechanism which will now be described.

20 As best shown in Fig. 5, each bracket 6 also provides a longitudinally extending sleeve 19 which is located between the supporting rod 7 and the bearing 10, and is adapted to journal a shaft 20 which extends 25 parallel to the axis of rotation of the drum 3. The shaft 20 extends beyond the adjacent end frame 1 and is provided with a pulley 21, whereby it may be driven from a suitable source of power, not shown. The 30 other end of the shaft 20 carries a pinion 22, which, as best shown in Fig. 6, has its teeth in engagement with the openings 18 provided in the periphery of the flange 17 of the drum head 11. Thus, when the shaft 35 20 is rotated, it is adapted to also drive the drum 3 and with it the associated spool 2, by reason of the frictional engagement between the surface of the drum 3 and the barrel 5 of the spool 2, or the material being 40 wound thereon, it being evident that the heads 4 of the spool 2 entirely clear the brackets 6.

In order to further support each bracket 45 6, one end of the sleeve 19 which journals the shaft 20 is received in the boss 23 of a hanger 24 which is carried on a stud 25 received in the adjacent end frame 1. As best shown in Fig. 2, the end frame 1 provides a number of vertically spaced arms 26, each 50 having a notch 27, which on existing machines formerly served to support the shaft of a driving drum. In my improved arrangement however, the notch 27 receives the stud 25 which is clamped therein by means 55 of nuts 28. The end of the stud 25 is received in an elongated opening 29 provided in the upper end of the hanger 24, so that the hanger 24 may be clamped in different positions on the stud 25 by means of a nut 30 60 cooperating with a shoulder 31 provided on the stud.

From the foregoing, it is evident that each 65 of the drums 3 is adapted to be supported between the end frames 1 of the machine in such a manner that a rotative driving force

may be applied to the outer periphery thereof by a shaft disposed entirely beyond the enlarged heads 4 of the spool 2. With this arrangement, it is possible to employ a drum which is approximately half the diameter 70 of the spool heads 4, thereby giving plenty of room between the drums 3 for access to the parts of the machine. The driving mechanism of the present invention is therefore a distinct improvement over previous driving mechanisms, for the same purpose, in which the driving drums have been rotatably supported in the slots of the arms 26 of the end frames and the driving force applied directly to the axes of the drums. 75

80 My invention possesses a further advantage in that it may be readily applied to existing machines without necessitating any rearrangement of the essential parts thereof, it only being necessary to provide the cross rods 7 for supporting the brackets 6 for the drums 3. It is evident that the brackets 6 are capable of ready adjustment for supporting the drums 3 in proper position, by the provision of the set screws 32 for clamping each bracket 6 to its rod 7. Furthermore, each hanger 24 permits proper positioning of the sleeve 19 therein by means of a set screw 33, while the hanger itself is adapted for adjustment with respect to the end frame 95 through the provision of the elongated opening 29 for receiving the stud 25.

99 Thus each drum 3 and its driving mechanism may be readily installed and adjusted 100 between the end frames of a machine to drive a winding spool 2 supported in the proper position to receive the material to be wound thereon. In order to properly position the winding spools 2, a number of pairs of spool supporting arms 34 are mounted on 105 the rods 7 beyond the brackets 6, the arms 34 providing inclined portions 35, against which bear the stub shafts 36 provided by the ends of the spools 2, as clearly shown in Fig. 2. The arm portions 35 serve to guide 110 the upward movement of the spool barrels 5 away from the drums 3 as the material is wound on the barrels 5 by the rotation of the drums.

115 I claim,

1. In a machine of the class described, a 120 rotatably mounted drum, a winding spool having a central portion adapted to carry wound material in engagement with the periphery of said drum, and provided at its ends with enlarged heads embracing said drum, and a single rotatable shaft, with its axis disposed entirely outside the periphery of said drum, for applying a driving force thereto.

125 2. In a machine of the class described, a rotatably mounted drum, a winding spool having a central portion adapted to carry wound material in engagement with the periphery of said drum, and provided with en-

larged heads embracing the drum, with the axis of rotation of said drum lying within said heads when the spool is empty, and a single rotatable shaft, with its axis lying entirely outside of said drum, for applying a rotative force to the periphery of said drum.

3. In a machine of the class described, the combination with a pair of spaced end frames, of a pair of brackets mounted between said end frames for rotatably supporting a cylindrical drum between them, and means carried by one of said brackets for applying a rotative driving force directly to the outer periphery of said drum.

4. In a machine of the class described, the combination with a pair of spaced end frames, of a pair of brackets mounted between said end frames for rotatably supporting a cylindrical drum between them, and a shaft extending through one of said brackets for applying a rotative driving force directly to the outer periphery of said drum.

5. In a machine of the class described, the combination with a pair of spaced end frames, of a pair of brackets mounted between said end frames for rotatably supporting a cylindrical drum between them, and a shaft extending through one of said brackets parallel to the axis of said drum, said shaft carrying at one end a pinion located entirely outside of said drum, said pinion driving said drum by direct engagement with it.

6. In a machine of the class described, the combination with a pair of spaced end frames, of a pair of brackets mounted between said end frames for rotatably supporting a cylindrical drum between them, and a shaft extending through one of said brackets carrying at one end a pinion located entire-

ly outside of said drum with its teeth in engagement with a series of openings in the periphery of said drum.

7. In a machine of the class described, the combination with a pair of spaced end frames, of a pair of brackets mounted between said end frames for rotatably supporting a cylindrical drum between them, a shaft extending through one of said brackets with its axis located entirely outside of said drum, a pulley mounted on said shaft beyond one of the end frames, and a gear carried at the other end of said shaft for engaging the outer periphery of said drum.

8. In a winding mechanism for tape condensers and like machines, a pair of end frames, a shaft supported by said end frames, extending completely between them, brackets on said shaft, a driving cylinder rotatably held by said brackets, a drive shaft for said cylinder journaled in one at least of said brackets, and auxiliary supporting means for said brackets attached to said end frames.

9. In a winding mechanism for tape condensers and like machines, a pair of end frames, a shaft supported by said end frames, extending completely between them, brackets on said shaft, a driving cylinder rotatably held by said brackets, a drive shaft for said cylinder journaled in one at least of said brackets, and auxiliary supporting means for said brackets attached to said end frames, said auxiliary supporting means comprising hangers surrounding an extension of said brackets, horizontal projections from said end frame, and adjustable connections supporting said hangers from said projections.

JOSEPH F. SCHIMEK.
